UNITED STATES PATENT OFFICE.

ARTHUR P. ACKERMAN, OF GREAT BARRINGTON, MASSACHUSETTS.

ADJUSTABLE DIVISOR.

1,331,476.

Specification of Letters Patent.

Patented Feb. 24, 1920.

Application filed June 16, 1919. Serial No. 304,544.

To all whom it may concern:

Be it known that I, ARTHUR P. ACKERMAN, a citizen of the United States of America, residing at Great Barrington, county of Berkshire, State of Massachusetts, have invented certain new and useful Improvements in Adjustable Divisors, of which the following is a specification.

My invention relates to apparatus used by draftsmen for dividing a line or distance into a number of equal parts. The best form of apparatus embodying my invention at present known to me is illustrated in the accompanying two sheets of drawings in

which:

Figure 1 is a plan view of the apparatus extended and with parts broken away.

Fig. 2 is an end view of the apparatus.

Fig. 3 is a plan view of the apparatus closed together, parts being broken away.

Fig. 4 is a cross section on line 4—4 of Fig. 3, and

Fig. 5 is a cross section on line 5—5 of Fig. 3.

Throughout the drawings like reference characters indicate like parts. 21, is a scissor-like structure having the set screw 22, as a pivot. 23, 23, etc., are a series of pencil-like strips or pointer fingers located on the under surface of a set of lazy tong-like linkage and connected to that structure by means of slots 33, and perforations which engage with extension pivot pins 36, of the lazy tong-like linkage. 24, 24, are similar pointer strips or fingers located on the upper surface of the lazy tong-like linkage and connected thereto by slots 33, engaging extension pivot pins 34, of the lazy tongs.

The lazy tong-like structure is composed of the upper members 25, and the lower members 26, which are jointed together by pins 34, and 36, each member 25, having four points of pivotal connection to members 26, and vice versa, whereby there is formed what I will call a double set of lazy tong-like linkage. That is to say, one which has two complete series of pivot points running lengthwise of the set.

27, 27, are carrier bars connected to the lazy tong-like linkage at separate points and in line with certain of the pointer strips, the connection being such as to permit the opening and closing of the lazy tong-like linkage. These carrier bars have their outer ends bent upwardly from the plane of the lower surface of the lazy tong-like linkage,

as shown at 28, in Fig. 2, and these extensions may be connected by hinges 29, 29, whose axes are in a plane parallel to the plane of the lazy tong-like linkage, to short links 39, 39, which are pivoted to the free ends of the scissor-like structure 21, at 38, 38. The effect of this construction is to give the scissor-like structure a universal joint connection with the lazy tong-like linkage so that the lazy tongs and the scissor-like handle may open and close freely, even though the lazy tong-like linkage lies in one plane, such as the plane of the paper on which they rest, and the scissor-like structure lies in another plane so as to permit the same to extend upward away from the plane of the paper to allow the operator to conveniently grasp the same. A strip in the center of each carrier bar section 28, is bent upward forming a lug 37, and similar lugs are formed on links 39, 39. These lugs prevent the scissor-like structure 21, from resting on the pointers when folded completely over.

It is evident from the foregoing description that when the operator opens and closes the scissor-like structure 21, the linkage structure will open and close at the same rate, and the pointer strips 23, 24, will be moved toward and from one another equal distances and will always remain parallel one to another. In order to insure that the points of these pencil-like strips or pointers shall always be in the same line, I employ a series of short guide links 30, 30, one end of each of which is pivoted to the end of one of the set of pointer strips 24, by pivot pin 31, while the other end is pivoted to one of the linkage members 25, 25, by a pin 35. The pin 35 is located half way between the adjacent pivot pins 34, and 36, of the lazy tong-like linkage and the length of the guide link 30, between centers of pins 31 and 35, is equal to the distance between the centers of the pins 36 and 35. As the lazy tong-like linkage open and close this guide link 30, will cause each pointer strip to slide along its slotted connections with the pivots 34, 34, of the lazy tong-like linkage so as to be always in the same position relative to the adjacent pointer strips 23, 23. Consequently the pointer ends of all the pointer strips 23, and 24, will be in the same plane, and if the pointed ends of one set of strips, as 24, are bent downward, as shown in Fig. 2, all the points of all the pointer strips will always be in one and the same straight line

as the lazy tong-like linkage is opened and closed.

32, represents washers used between certain of the parts to permit them to lie in different planes spaced far enough apart so that the different members may nest together closely as shown in Figs. 3, 4 and 5, when the lazy tong-like linkage is closed, and without the heads of the pivot pins interfering with this nesting action.

To operate my invention, the user loosens the set screw pivot 22, and grasps the scissor-like structure 21, as he would grasp a pair of scissors, opens the lazy tong-like linkage far enough so that two of the pointer strips may rest on two points on the drawing, which are a distance apart equal to the distance which is to be divided into a number of equal parts. If this distance was to be divided into twelve parts, then one pointer would rest upon one point and the lazy tong-like linkage would be opened or closed until the thirteenth pointer rested on the other point of the drawing. Each of the intermediate pointers would be then separated from its neighbor by a distance which would be one-twelfth of the distance between the two points originally selected. To facilitate this the pointers will be numbered beginning with 0 on the left and reaching 20, on the right, as shown. In like manner the apparatus could be used for other purposes. To hold the apparatus in any position of adjustment the set screw 22, is screwed down again.

Among the advantages of my invention are the following: It may be cheaply made out of stamped metal parts. It can be operated with one hand conveniently, while the draftsman can hold his pencil in the other hand for making the necessary markings. By having the two sets of pointers in different places, double the usual number of pointers is secured for a given size of lazy tong-like linkage.

Various changes could be made in the details of construction here illustrated and described without departing from the substance of my invention so long as the general principles of operation and construction above set forth are retained.

Having described my invention, I claim:

1. The combination with a lazy tong-like linkage and a plurality of pointers mounted on different elements of said linkage, of a scissor-like structure, the free ends of which are pivoted to the linkage at separate points along the edge thereof whereby the opening or closing of the scissor-like structure will cause the linkage to expand or contract and cause the pointers to separate from or approach one another by equal increments of distance.

2. A combination such as set forth in claim 1, in which the pointers consist of

pencil-like strips arranged parallel each to all the others, and having pin-and-slot connections with certain of the lazy tong's pivots.

3. A combination such as set forth in claim 1, in which the pointers consist of pencil-like strips arranged parallel each to all the others, and having pin-and-slot connections with certain of the pivots of the lazy-tong-like linkage, together with means for maintaining the extremities of all the pointers in a straight line during the opening or closing of the linkage.

4. The combination, with a lazy tong-like linkage and a plurality of pointers mounted on different elements of the linkage, of a scissors-like structure, the free ends of which are pivoted to the linkage at different points by universal joints, whereby the linkage may be operated by the scissors-like structure while held at any inclination to the plane of the linkage, and the two may be folded together when not in use.

5. A structure such as set forth in claim 1, combined with a set screw on the scissor-like structure adapted to hold the parts in any position of adjustment.

6. The combination with a lazy tong-like linkage of a series of pencil-like pointer strips extending across the linkage at right angles to the major dimension thereof when it is extended and connected to the pivot pins of the linkage by means freely permitting the expansion and contraction of the linkage, every alternate member of the series of pointer strips being located and fastened on the upper surface of the linkage, the others being located and fastened on the under surface, and the points of one such series of strips being bent into line with the points of the other series.

7. A combination such as set forth in claim 6, in which the fastening means comprises slots in the pointer strips extending lengthwise thereof, and extensions on certain of the lazy tong-like linkage pivot pins engaging said slots.

8. The combination of a lazy tong-like linkage having certain of its pivot pins extended, a plurality of pointer strips divided into two series; one of which comprises the first, third, fifth, etc. of the strips while the other comprises the second, fourth, sixth, etc., said strips having slots and perforations with which the extended pivot pins may engage, and a plurality of short guide-links, each of which is pivoted at one end to a member of one of the series of pointer strips and at the other to the linkage, whereby on the opening or closing of the linkage the pointer strips may slide along their slotted connections with the linkage under the control of their pivotal connections therewith and with the guide links, so that the

extremities of the pointers are always held in line one with another.

9. The combination of a double lazy tong-like linkage having some of its pivot pins extended, a series of pointer strips pivoted one to each pivot pin of the set located along one edge of the linkage, and having a slotted connection with the corresponding pivot pin of the set located near the other edge of the linkage, a second series of pointer strips having slotted connections with the pivot pins of the set located along the said other edge of the linkage and with the corresponding pivot pins of the set located near the first mentioned edge of the linkage, and a plurality of short guide links each of which is pivoted at one end to a member of the second set of pointer strips and at the other to an element of the linkage, whereby on the opening or closing of the linkage the pointer strips have their pivotal connections held in line, while their

slotted connections to the linkage permit the necessary relative movements of the various elements thereof.

25

10. A combination such as set forth in claim 9, in which all members of one series of pointer strips are located on one surface of the lazy tong like linkage set and all members of the other series are located on the other surface and the projecting ends of one series of pointers are bent into line with those of the other series.

30

11. A combination such as set forth in claim 1, in which the members of the scissors-like structures are provided with hinges permitting it to be folded over on the linkage, and with coöperating spacing lugs adapted to prevent the scissors touching the linkage when so folded over.
